[57] **CLAIM**

The ornamental design for a haptic end portion of the intraocular lens, as shown and described.

DESCRIPTION

FIG. 1 is a perspective view of a haptic end portion of the intraocular lens showing my new design, the broken lines are for illustrative purposes only and form no part of the claimed design;

FIG. 2 is a side elevational view of FIG. 1;

FIG. 3 is an enlarged perspective view thereof;

FIG. 4 is a cross sectional view taken along lines 4—4 of FIG. 3;

FIG. 5 is a perspective view of a second embodiment of the haptic end portion of the intraocular lens;

FIG. 6 is a side elevational view of FIG. 5;

FIG. 7 is an enlarged perspective view of FIG. 5; and,

FIG. 8 is a cross sectional view taken along lines 8—8 of FIG. 7.
